(57) **CLAIM**

The ornamental design for headphones, as shown and described.

DESCRIPTION

This application contains subject matter related to the following co-pending U.S. design patent application:

Application Ser. No. 29/393,297, filed herewith and entitled "Cable Storage in Headphones".

FIG. 1 is a perspective view of headphones according to my design, the perspective from the opposite side being mirror symmetrical;

FIG. 2 is a side view thereof, the opposite side view being mirror symmetrical;

FIG. 3 is a front view thereof;

FIG. 4 is a rear view thereof;

FIG. 5 is a top view thereof; and,

FIG. 6 is a bottom view thereof.

The broken lines are for illustrative purposes only and form no part of the claimed design.

1 Claim, 4 Drawing Sheets

FIG. 2

FIG. 1

FIG. 3

FIG. 4

FIG. 5

FIG. 6
